United States Patent Office.

D. R. PRINDLE, OF EAST BETHANY, NEW YORK.

Letters Patent No. 77,528, dated May 5, 1868.

IMPROVEMENT IN FIELD-ROLLERS.

The Schedule referred to in these Letters Patent and making part of the same.

TO ALL WHOM IT MAY CONCERN:

Be it known that I, D. R. PRINDLE, of East Bethany, in the county of Genesee, and State of New York, have invented an improved Field-Roller; and I do hereby declare that the following is a full and exact description thereof, reference being had to the accompanying drawings making part of this specification—

Figure 1 being a vertical section through the centre of the rollers.

Figure 2, a vertical section in a plane indicated by the line $z z$, fig. 1.

Like letters designate corresponding parts in both figures.

I make the roller in two (or more) sections, A B; and the first feature of my improvement consists in the employment of a jointed axis or pivot, there being a section, a and b , respectively for each section A and B of the roller, and jointed together, at $m n$, between the two sections of the roller. This jointing together of the sections of the axis, while it allows the sections of the roller to adapt themselves to the uneven surface of the ground, causes the said sections always to move together, up or down, and to act in harmony with each other; and the whole construction and arrangement are simple and durable.

The bearings $c c$ of the frame C, in which the journals of the outer ends of the jointed-axis turn, are somewhat conical or flaring inward, as shown, in order to allow the vibratory movement of the axis, as above set forth.

In connection with the jointed axis of the roller, I employ a vertically-oblong bearing, d , in the frame, for the axes between the sections of the roller, so as to allow a free vertical movement of the jointed axis, while it is rigid and unbending horizontally, so that the sections of the roller pass firmly over the ground, while they adjust themselves to the irregularities of the ground's surface. Instead of a single guide or bearing, d , there may be two, one for each section of the axis, but this is not necessary.

The other parts of the roller need not be of unusual construction, and require no description.

What I claim as my invention, and desire to secure by Letters Patent, is—

The jointed axis or pivot $a b$, for two or more sections, A B, of a roller, substantially as and for the purpose herein specified.

I also claim the vertically-oblong or upright bearing d , between the sections of the roller, substantially as set forth.

I also claim the combination of the jointed axis or pivot, and the vertically-slotted or oblong bearing, so as to produce a roller which will adapt itself up and down to the unevenness of the ground, but will be rigid in a horizontal direction, substantially as herein specified.

The above specification of my improved field-roller signed by me, this eighth day of February, 1868.

D. R. PRINDLE.
